UNITED STATES PATENT OFFICE.

ARTHUR L. EDWARDS, OF LEWISTOWN, MONTANA.

DRILL-BIT.

1,113,968.

Specification of Letters Patent.

Patented Oct. 20, 1914.

Application filed November 12, 1913. Serial No. 800,655.

To all whom it may concern:

Be it known that I, ARTHUR L. EDWARDS, a citizen of the United States, residing at Lewistown, in the county of Fergus, State of Montana, have invented certain new and useful Improvements in Drill-Bits; and I do hereby declare the following to be a full, clear, and exact description of the invention, such as will enable others skilled in the art to which it appertains to make and use the same.

This invention relates to drill bits and particularly to that type employed in drilling water, oil and gas wells and in analogous operation.

The object of the invention resides in the provision of a drill bit which will cut a hole of greater diameter than the exterior diameter of the casing in which the bit is operated whereby said casing may be easily and conveniently advanced as the depth of the bore increases.

A further object of the invention resides in the provision of a drill bit of the character named which will be simple in construction, efficient in use, and which may be manufactured at a comparatively small cost.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a vertical section of a well drilling casing showing the improved bit therein, said bit being in the position it would occupy before completing its drilling stroke; Fig. 2, a view similar to Fig. 1 showing the bit at the termination of its drilling stroke; Fig. 3, a side elevation of the bit detached; Fig. 4, a section on the line 4—4 of Fig. 3; Fig. 5, a section on the line 5—5 of Fig. 3, and Fig. 6, an end view of the bit looking at the cutting edge thereof.

Referring to the drawings the bit is shown as comprising a body A including a cylindrical knuckle portion 10, one end of which is reduced and threaded as at 11 whereby same may be connected to the usual drill

tools. The body A outwardly of the knuckle 10 is substantially semi-cylindrical in cross section and is provided with opposite flat faces 12 whereby same may be gripped with a tool for the purpose of screwing the bit into a well drilling tool. The extreme outer end of the body A is flared outwardly as at 13 and provided with a cutting edge 14. It will be noted that the diameter of the cylinder of which the semi-cylindrical portion of the body forms a part is equal to or less than the interior diameter of the casing which is indicated at 15 whereby the bit is capable of a certain amount of lateral movement within the casing. It will be further noted in this connection that the cutting edge 14 is located in a circle having a greater diameter than the diameter of the cylinder of which the semi-cylindrical portion of the body forms a part. The flat face of the semicylindrical portion of the body is provided with longitudinal grooves 16 and 17 forming a central rib 18 the outer end of which terminates in a cutting edge 19. Secured against one of the flat faces 12 and engaged in a socket 20 formed in one end of the knuckle 10 is one end of a bow spring 21. The outer end of this bow spring 21 is provided with a longitudinal slot 22 and engages the outer edge of the rib 18. Extending through the slot 22 and engaged in the rib 18 is a screw 23 which permits sliding movement of the adjacent end of the spring 21 as will be obvious. The side portions of the spring 21 adjacent the slot 22 are bent into embracing relation to the rib 18 whereby lateral movement of the spring with respect to the rib is prevented as is likewise strain upon the screw 23 that would arise from a tendency of the spring 21 to move laterally with respect to the rib 18.

In the use of the bit it will be obvious that when same is entirely confined in the casing 16 the spring 21 will be tensioned. With this status existing it will be apparent that when the bit reaches the termination of its cutting stroke the cutting edge 19 and flared portion 13 will pass out of the casing and the spring 21 will automatically operate to throw the cutting edge laterally and thus produce a boring having a diameter in excess of the exterior diameter of the casing whereby the latter can be advanced without trouble as the boring progresses.

What is claimed is:—

A drill bit for boring tools comprising a shank of a size to move laterally in an associated casing, said shank having a cutting edge disposed outwardly of the side limits of the remainder of said shank, and a bow spring having one end fixed to the shank and its other end slidably engaged therewith, said spring being adapted to 5 operate with an associated casing to constantly tend to move the shank laterally in 10

the casing whereby the cutting edge will be shifted to a position outwardly of the exterior limits of the casing when said cutting edge has been moved out of the casing.

In testimony whereof, I affix my signature in the presence of two witnesses.

ARTHUR L. EDWARDS.
